UNITED STATES PATENT OFFICE.

EDWARD P. BEACH, OF NEWARK, NEW JERSEY, ASSIGNOR TO UNGER BROTHERS, OF SAME PLACE.

DESIGN FOR A BROOCH OR SIMILAR ARTICLE.

SPECIFICATION forming part of Design No. 20,518, dated February 10, 1891.

Application filed December 26, 1890. Serial No. 375,861. Term of patent 3½ years.

To all whom it may concern:

Be it known that I, EDWARD P. BEACH, a citizen of the United States, residing at Newark, in the county of Essex and State of New Jersey, have invented and produced a new and original Design for a Brooch or Similar Articles; and I do hereby declare the following to be a full, clear, and exact description of the invention, such as will enable others skilled in the art to which it appertains to make and use the same, reference being had to the accompanying drawing, and to letters of reference marked thereon, which form a part of this specification.

Referring to said drawing, the same represents a front or plan view of my newly-designed jewelry ornament, which is deemed sufficient to fully illustrate my design.

The leading feature of my design consists in the peculiar form and in the arrangement of the several parts or sections thereof, each of which parts the thread of which is round in cross-section is in the form of a flat spiral.

These spirals are arranged to overlap and join one another, so as to form upon the 25 periphery of the ornament a series of uniform or nearly uniform curves *a*, and leaving at the center an open space for a stone or pearl and a setting *b* therefor, as indicated in the drawing. The body of the ornament, except 30 where the several parts or sections join or overlap one another, shows a series of openings of irregular form, which add beauty and lightness thereto. The number of sections which may be employed is immaterial. 35

What I claim, and desire to secure by Letters Patent of the United States, is—

The design for a brooch or similar article herein shown and described.

In testimony that I claim the foregoing I 40 have hereunto set my hand this 19th day of December, 1890.

EDWARD P. BEACH.
